[57] CLAIM

The ornamental design for a automobile body, as shown and described.

DESCRIPTION

FIG. 1 is a side elevational view of an automobile body showing my new design;

FIG. 2 is a left side elevational view thereof;

FIG. 3 is a front elevational view thereof;

FIG. 4 is a rear elevational view thereof; and,

FIG. 5 is a top plan view thereof.

The broken lines shown in FIGS. 1, 2, 3 and 4 of the drawing are for illustrative purposes only and form no part of the claimed design.
